UNITED STATES PATENT OFFICE

CYRUS A. BRYANT, OF PASSAIC, NEW JERSEY, ASSIGNOR TO V. M. SALES CO., OF PLAINFIELD, NEW JERSEY.

DRINKING-CUP.

1,050,100.

Specification of Letters Patent. Patented Jan. 14, 1913.

Application filed October 17, 1911. Serial No. 655,118.

To all whom it may concern:

Be it known that I, CYRUS A. BRYANT, a citizen of the United States, and a resident of Passaic, in the county of Passaic and 5 State of New Jersey, have invented a new and Improved Drinking-Cup, of which the following is a full, clear, and exact description.

The object of the invention is to provide 10 a new and improved drinking cup preferably of paraffin paper or other similar waterproof material, and arranged to permit of nesting a large number of cups in a comparatively small space, the said method 15 permitting of manufacturing the cup at a low expense.

The drinking cup is in the form of the 20 frustum of a cone and formed from a single sheet of paper or similar material doubled up and having sides connected with each other, the bottom being flat and onto which fold ears fastened in place by a separate disk, glued, pasted or otherwise fastened to the said flat bottom and the overlapping 25 ears.

A practical embodiment of the invention 30 is represented in the accompanying drawings forming a part of this specification, in which similar characters of reference indicate corresponding parts in all the views.

Figure 1 is a side elevation of a flat vessel 35 made from a single sheet of paper or other material; Fig. 2 is an edge view of the same, partly opened up; Fig. 3 is a perspective view of the same after being fully opened; Fig. 4 is a like view of the same 40 after the ears are pressed inward and down onto the closed flat end of the vessel; Fig. 5 is a perspective view of the finished drinking cup upside down; Fig. 6 is a like view of the same right side up; and Fig. 7 is a plan view of the same.

The drinking cup is formed from a single 45 sheet of paraffin paper or other material rendered waterproof, the sheet being doubled up, and one of the doubled-up members being provided at the sides with side flanges A' folded onto the other member and fastened thereto to form a flat vessel, 50 as shown in Fig. 1, the vessel having sides A², a closed end A³ and an open end A⁴.

The closed end A³ is in the form of a sharp edge, and in order to form this flat-

vessel into a drinking cup of the shape of the frustum of a cone, I proceed as follows: 55 The sides A² of the flat vessel A are exteriorly engaged by suction devices B adhering to the said sides, and on being pulled apart partly open up the vessel A, as plainly indicated in Fig. 2. The open end A⁴ of 60 this partly opened up vessel is now placed over a form C, and pressure is exerted on the middle portion of the closed end A³ by a suitable pressing device D so that the vessel is pressed down on the form C and 65 the air confined in the closed end of the vessel is compressed to cause the vessel to open up fully at the closed end with a view to conform to the conical shape of the 70 form C. By this downward pressure on the end A³ of the vessel A the closed end A³ is formed into a flat bottom A⁵ of approximately disk shape with the sides forming upwardly-extending ears A⁶, owing to the 75 fact that the said sides are not subjected to pressure by the pressing device D. Suitable fingers E now engage the ears A⁶ at the outer sides thereof to press the ears A⁶ inward and downward onto the flat bottom A⁵ of the vessel, as plainly indicated in Fig. 4. 80

It is understood that when the vessel is 85 pressed down on the form C the air is compressed sufficiently to open up the closed end of the vessel, at the same time allowing the air to escape between the inner surface 90 of the sides A² of the vessel and the outer surface of the form.

After the vessel has been given the shape 95 of the frustum of a cone, as described, a fastening disk F, of paper or other similar material, is pasted, glued or otherwise attached to the bottom of the drinking cup so as to hold the ears A⁶ down upon the flat bottom A⁵.

By constructing the drinking cup in the 100 manner described, a large number of such cups can be readily nested to take up very little room, and by the method described the drinking cup can be cheaply manufactured and sold at a low price.

It is understood that drinking cups of this kind are intended to be used but once and then thrown away, especially when a person makes use of public fountains or other similar water supplies.

Having thus described my invention, I

claim as new and desire to secure by Letters Patent:

As an article of manufacture, a drinking cup having a body in the form of a frustum 5 of a cone and formed of a single sheet of paper doubled up, one of the doubled-up members having side flanges folded onto and secured to the other doubled-up member, the integral bottom of the cup being approximately 10 in the shape of a disk formed of equal portions of the said doubled-up members, and ears formed of portions of the said flanges and portions of the said

doubled-up members and fastened to the underside of the said bottom, the said ears 15 being approximately triangular in shape and the apexes being spaced apart, and a bottom disk overlying the said ears and bottom and fastened thereto.

In testimony whereof I have signed my 20 name to this specification in the presence of two subscribing witnesses.

CYRUS A. BRYANT.
